UNITED STATES PATENT OFFICE

SEVERIN N. GUNDLACH, OF BELLEVILLE, ILLINOIS

SHINGLE CUTTER

Application filed May 2, 1929. Serial No. 359,739.

This invention relates to cutting devices, particularly shingle cutters such as are used by roofers and has for its principal objects to provide an efficient lightweight shingle cutter which will successfully cut asbestos shingles of different thicknesses and which can be easily carried about and secured to the roof; to provide means for punching nail holes in the shingles; and to provide for simplicity and cheapness of construction and compactness of design. The invention consists in the shingle cutter and in the construction, combination and arrangements of parts hereinafter described and claimed.

In the accompanying drawings, which forms part of this specification and wherein like symbols refer to like parts wherever they occur,

Fig. 1 is a side elevation of a shingle cutter embodying my invention;

Fig. 2 is an end view of the cutter, showing the lever for raising and lowering the free end of the pivoted knife carrier;

Fig. 3 is a view looking at the hinged end of said cutter;

Fig. 4 is a vertical section on the line 4—4 in Fig. 1.

Fig. 5 is a vertical section through the hinged knife carrier on the line 5—5 in Fig. 30 1; and

Fig. 6 is a vertical section through said pivoted knife carrier on the line 6—6 in Fig. 1.

My cutting device is particularly adapted for use in cutting asbestos shingles, although it may be used for other purposes. Said cutter comprises a stationary main body member 1 provided adjacent to its ends with laterally extending foot flanges 2 that extend far enough on opposite sides of said body member to hold the same in upright position. The foot flanges are provided intermediate their ends with notches 3 and at their outer ends with laterally extending upwardly offset lugs

4 having nail holes 5 therein. By this arrangement the cutter may be readily secured to the roof by nails driven into the sheathing and engaged with the notches 3 of the foot flanges 2 or by placing said foot flanges in abutting relation to the side edges of tim-

bers with the lugs overlapping the same and preferably secured thereto by nails driven through the holes 5. The stationary body member 1 of the cutter is provided along its top with a longitudinal groove 6 adapted to receive a knife blade 7 which is removably secured in said groove by means of set screws 8. The upper edge of the knife blade 7 projects above the upper edge of the main body member 1 and is provided with a beveled cutting edge. The body member is provided along one side with a laterally extending flange portion 9 which serves as a support or table for the shingle being cut and to reinforce and stiffen the body member against cross-bending.

Located above the body member 1 of the cutter is a knife carrier 10 that is pivotally supported at one end of said main body member for vertical swinging movement towards and away from the stationary knife blade 7. Mounted in a longitudinal groove 11 in the underside of the pivoted knife carrier 10 is a knife blade 12 which is provided along its lower edge with a longitudinal V-shaped cutting edge disposed in vertical alignment with the cutting edge of the stationary lower knife blade. The upper knife blade 12 may be adjusted relative to the stationary knife blade 7 to enable the material to be cut without damage thereto, by means of a series of adjusting screws 13 that are threaded into the pivoted carrier 10 with their lower ends in abutting relation to the top of said upper knife blade. The adjusting screws are locked in adjusted position by lock nuts 14; and the upper knife blade 12 is locked in the desired adjusted position in the groove 11 in the pivoted knife carrier 10 by means of set screws 15 that are threaded into said knife carrier and bear against the side of said knife blade.

The pivot 16 for supporting the vertically swinging knife carrier 10 is mounted on the upper end of a threaded stud 17, which is slidably mounted in vertically aligned openings in two vertically spaced lugs 18 that project horizontally from one end of the body member 1. The stud is adjusted vertically in the openings in the lugs 18 by means of

a nut 19 which is threaded on said stud between said lugs and is held against the upper lug by means of a coiled supporting spring 20 sleeved on said stud between the lower lug and said adjusting nut. By this arrangement, the pivot 16 of the knife carrier may be raised and lowered for shingles of different thicknesses by turning the nut 19 on the stud 17, which is prevented from turning by reason of its pivoted connection with the body member 1. The body member 1 is provided adjacent to the vertically adjustable pivot supporting stud 17 with a scale 21 which is graduated to give readings in fractions of an inch; and the stud 17 is provided with a collar 22 whose lower edge when opposite a graduation indicates that the pivoted knife carrier 10 is in proper adjustment for cutting shingles having a thickness corresponding to the thickness indicated opposite said graduation.

The pivoted knife carrier 10 is raised and lowered by means of a lever 23 provided, with arms 24, 25 and 26. The arm 24 is provided with a socket adapted to receive one end of an operating handle 27; the arm 25 is pivotally secured by means of a horizontal pivot 28 to the upper end of a link 29 whose lower end is secured to the adjacent end of the stationary or main body portion of the cutter by means of a horizontal pivot pin 30; and the arm 26 is pivotally secured between a pair of upstanding ears 31 on the free outer end of the pivoted knife carrier 10 by means of a horizontal pivot pin 32 which extends through axially aligned horizontal openings in the ears 31 and arm 26. The pivoted knife carrier 10 is normally held in raised position by means of a spring 33, which bears against the operating lever 23 and has its end portions coiled around the ends of the pivot pin 32 and hooked around the ears 31 on said knife carrier. With this arrangement, when the lever 23 is operated to swing the knife carrier downward the coils of the spring 33 are tightened and when the pressure is released said coils partially unwind and operate to return the knife carrier, operating lever and supporting link to their normal positions. The arm 25 of the lever 23 is provided with outstanding lugs 34, adapted in the raised position of the pivoted knife carrier to abut against similar outstanding lugs 35 on the adjacent free end of said carrier and thus limit the upward swinging movement thereof. The free end of said knife carrier is also provided with a pair of outstanding lugs 36 adapted to straddle the lower supporting link 29 and prevent side play of the parts and thus maintain the cutting edges of the knives in parallel alinement.

The cutting device is provided with means for punching a nail hole in the shingle. As

shown in the drawing, said means comprises an upright punch plunger 37 slidable in axial aligned holes provided therefor in a pair of vertically spaced outstanding lugs 38 on one side of the pivoted knife carrier. The punch plunger 37 is normally held in raised position by means of a coil spring 39 interposed between the lower lug and a collar 40 on said plunger, which collar abuts against the upper lug and thus limits the upward sliding movement of the punch plunger. The upper end of the punch is provided with a knob 41, and its lower end cooperates with a hole 42 formed in an outstanding bracket 43 on the side of the stationary body portion 1 of the cutter. The bracket is bossed up around the hole and at opposite sides thereof, thereby forming a three-point rest for the shingle during the punching operation.

The hereinbefore described cutting device has numerous advantages. Its light weight and compactness enables it to be easily carried up to and about the roof. It can be quickly and easily secured in position on the roof and can be operated with little effort by reason of the powerful lever arrangement. It may be readily adjusted for shingles of different thicknesses; and it provides a wide opening between the knife blades; thereby permitting the shingles to be quickly and easily inserted therebetween.

Obviously, the hereinbefore described cutting device admits of considerable modification without departing from the invention. Therefore, I do not wish to be limited to the precise construction shown and described.

What I claim is:

1. A cutting device comprising a body portion, a knife blade mounted therein, a knife carrier located above said body member and pivotally secured thereto, a knife blade mounted in said pivoted carrier for cooperation with the knife blade on said body member, means mounted on said body member and operatively engaging the free end of the pivoted knife carrier to actuate the latter, and means for varying the pivot point of said pivoted knife carrier, said means comprising a threaded stud slidably mounted on said body member and pivotally supporting said knife carrier, a spring for supporting said threaded stud, and a nut threaded on said stud and adapted to be held in abutting relation to said body member by the action of said stud supporting spring.

2. A shingle cutter comprising a body portion, a knife blade mounted therein, a knife carrier located above said body member and pivotally secured at one end thereto, a knife blade mounted in said pivoted carrier for cooperation with the knife blade on said body member, means mounted on said body member and operatively engaging the free end of

the pivoted knife carrier to actuate the latter, and means for adjusting the pivot point of said pivoted knife carrier, said means comprising a threaded stud mounted for vertical sliding movement on said body member and pivotally supporting said knife carrier, a spring mounted on said body member for supporting said threaded stud, a nut threaded on said stud and adapted to be held in abutting relation to said body member by the pressure of said spring, a scale on said body member, and means on said stud cooperating with said scale.

3. A portable shingle cutter comprising a body portion provided adjacent to its ends with laterally extending foot flanges provided with outstanding upwardly offset perforated lugs, a knife carrier located above said body member and pivotally secured thereto adjacent to one end thereof, cooperating knife blades on the body member and said pivoted knife carrier, a link pivoted at its lower end to said body member adjacent to the free end of said knife carrier, and an operating lever comprising an arm fulcrumed on the upper end of said link, an arm adapted to receive an operating handle, and an arm pivotally connected to the free end of said pivoted knife carrier.

4. A portable shingle cutter comprising a body portion provided adjacent to its ends with laterally extending foot flanges provided intermediate their ends with notches and adjacent to their ends with outstanding upwardly offset perforated lugs, a knife carrier located above said body member and pivotally secured thereto adjacent to one end thereof, cooperating knife blades on said body member and said pivoted knife carrier, a link pivoted at its lower end to said body member adjacent to the free end of said pivoted knife carrier, an operating lever having an arm fulcrumed on the upper end of said link, an arm adapted to receive an operating handle, and an arm pivotally connected to the free end of said pivoted knife carrier, and a spring cooperating with said lever and the free end of said knife carrier for normally maintaining the latter in raised position.

5. A portable shingle cutter comprising a body portion provided adjacent to its ends with laterally extending foot flanges provided intermediate their ends with notches and adjacent to their ends with outstanding upwardly offset perforated lugs, a knife carrier located above said body member and pivotally secured thereto adjacent to one end thereof, cooperating knife blades on the body member and said pivoted knife carrier, a link pivoted at its lower end to said body member adjacent to the free end of said knife carrier, an operating lever having an arm fulcrumed on the upper end of said link, an arm adapted to receive an operating handle, and

an arm pivotally connected to the free end of said pivoted knife carrier, a spring cooperating with said lever and the free end of said knife carrier for normally maintaining the latter in raised position, and means on said operating lever cooperating with means on the free end of said pivoted knife carrier for limiting the upward swinging movement of the latter.

6. A portable shingle cutter comprising a body portion provided adjacent to its ends with laterally extending foot flanges, a knife carrier located above said body member and pivotally secured thereto adjacent to one end thereof, cooperating knife blades removably mounted on the body member and said pivoted knife carrier, a link pivoted at its lower end to said body member adjacent to the free end of said knife carrier, an operating lever having an arm fulcrumed on the upper end of said link, an arm adapted to receive an operating handle, and an arm pivotally connected to the free end of said pivoted knife carrier, a spring cooperating with said lever and the free end of said knife carrier for normally maintaining the latter in raised position, means on said operating lever cooperating with means on the free end of said pivoted knife carrier for limiting the upward swinging movement of the latter, and a spring supported punch plunger slidably supported on said pivoted knife carrier.

7. A portable shingle cutter comprising a body portion, a knife carrier located above said body member and pivotally secured thereto adjacent to one end thereof, cooperating knife blades on the body member and said pivoted knife carrier, and means for adjusting the pivot point of said pivoted knife carrier, said means comprising a member slidably mounted on said body member and pivotally supporting said knife carrier, a member adjustably mounted on said slideable member, and a spring for supporting said slideable member with the adjustable member thereon in abutting relation to said body member.

8. A portable shingle cutter comprising a body portion, a knife carrier located above said body member and pivotally secured thereto adjacent to one end thereof for vertical swinging movement, cooperating knife blades removably secured to longitudinal meeting edges of said body member and said pivoted knife carrier, a link pivoted at its lower end to said body member for vertical swinging movement longitudinally of said knife blades, an operating lever comprising an arm fulcrumed on the upper end of said link, an arm adapted to receive an operating handle, and an arm pivotally connected to the free end of said pivoted knife carrier, a spring cooperating with said lever and the free end of said knife carrier for normally maintaining the latter in raised position, the

free end of said pivoted knife carrier being provided with a notch adapted to receive said link, and means on said operating lever co-operating with means on the free end of said pivoted knife carrier for limiting the upward swinging movement of the latter.

Signed at St. Louis, Missouri, this 30 day of April, 1929.
